UNITED STATES PATENT OFFICE

2,518,231

FOWL SLAUGHTERING DEVICE

Lawrence K. Fudge, Berthoud, Colo., assignor to
Alexander B. Pickands, Chicago, Ill.

Application June 30, 1948, Serial No. 36,059

2 Claims. (Cl. 17—11)

1

My invention relates to certain new and useful improvements in fowl slaughtering devices. It has for its principal object the provision of an improved construction of this character which will be highly efficient in use and economical in manufacture.

A principal object of the invention is the provision of a device of this character having a body receiving tube open at its lower end whereby a fowl projected into said tube head first, will be disposed in said tube with its head projecting substantially from the open end thereof so that the head may be conveniently grasped in one hand while operated upon by a sticking tool for puncturing the brain of the fowl.

Another object of the invention is to provide below a fowl-receiving tube, a drip box communicating with a suitable drain pipe for draining and collecting the drippings for suitable disposal thereof.

Finally an object of the invention is to provide a device of this character which will be substantially sanitary.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention; and

Fig. 2 is a vertical sectional detail view of the same.

In carrying my invention into effect, I provide a mounting structure indicated generally at 10. This mounting structure includes a base plate 11, a back wall 12 and side walls 13.

Supported from the upper portion of the back wall 12 by means of straps 14 or the like, and spaced from the back wall 12 by a spacing block 15, is a tube 16. This tube 16 is open at its opposite end portions and is funnel-shaped. In this tube 16, the fowl to be slaughtered is projected. The tube, being funnel-shaped, prevents the fowl from passing therethrough and allows the fowl to be projected into the tube a sufficient distance such that the neck 17 of the fowl will project from the lower open end portion of the tube a sufficient distance to allow the neck to be grasped by the hand 18 during the slaughtering operation accomplished by means of a piercing tool 19 held in the other hand 20. In this slaughtering operation, it is the practice to pierce the head of the fowl so as to puncture the brain and allow the blood to drain from the fowl. This

2

draining is accomplished while the fowl is retained in the tube 16. The drippings from the fowl pass into a dripping box 21 having a funnel-shaped bottom 22. This funnel-shaped bottom 22 is positioned in an opening 23 formed in the base plate 11. The funnel-shaped bottom terminates into a neck 24 which projects into the upper end portion of a drain pipe 25 leading to a suitable dispenser or pan (not shown).

10 The upper portion 26 of the front wall 27 of the box 21 is hinged as at 28 to the lower portion 29 of this wall 27. This hinged portion of the front wall has integrally formed portions 30, abutting the side walls 31 of the box. The arrangement is such that the hinged wall portion 26 may be pivoted outwardly to afford sufficient room at the base of the tube for the slaughtering operation.

15 The outward pivotal movement of this wall portion 26 is limited by chain elements 31' attached as at 32 to the wall portion 26 and to the side walls 13 of the mounting structure. A spring 33 normally holds the hinged wall portion 26 in its closed up-right position.

20 The mounting structure 10 may be fixed to a suitable table 34 or to a supporting structure.

25 From the foregoing description it will be apparent that I have provided a fowl slaughtering device which clearly facilitates the slaughtering of the fowl. The device also affords sanitary means for collecting for disposal the drippings from the fowl after the slaughtering operation.

The device is simple in construction and may be manufactured at an economical cost.

30 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

35 Having thus described my invention, what I claim as new and desire to protect by Letters Patent is:

1. A fowl slaughtering device comprising a mounting structure, a funnel-shaped tube carried by the upper end portion of the mounting structure and open at opposite end portions, a dripping box carried by the lower end portion of the mounting structure beneath the lower open end portion of the tube, said open end portion of the tube extending into said box, and a drain pipe communicating with said dripping box, said dripping box having a hinged wall portion movable

outwardly from the lower end portion of the tube to provide a working area surrounding said lower end portion of the tube.

2. A fowl slaughtering device comprising a mounting structure, a funnel-shaped tube carried by the upper end portion of the mounting structure and open at opposite end portions, a dripping box carried by the lower end portion of the mounting structure beneath the lower open end portion of the tube, said open end portion of the tube extending into said box, and a drain pipe communicating with said dripping box, said dripping box having a funnel-shaped bottom providing a neck portion insertable in said drain pipe, said dripping box having a hinged wall portion movable outwardly from the lower end portion of the tube to provide a working area surrounding said lower end portion of the tube.
